BARBECUE GRILL

Chan Ming-Kong, Kowloon, Hong Kong, assignor to
Chung Mei Manufactory Ltd., Tokwawan, Kowloon,
Hong Kong

Filed Sept. 14, 1972, Ser. No. 288,909

Claims priority, application Great Britain May 3, 1972

Term of patent 14 years

Int. Cl. D7—02

U.S. Cl. D7—110

FIG. 1

FIG. 2

FIG. 3

FIG. 4

FIG. 5

FIG. 6

FIG. 1 is a top perspective view from one side of the barbecue grill showing my new design;

FIG. 2 is a bottom perspective view thereof taken from the other side;

FIG. 3 is a top plan view thereof;

FIG. 4 is a bottom plan thereof from which the supporting tray has been omitted;

FIG. 5 is a part-sectional side elevation thereof; and

FIG. 6 is a sectional side elevation thereof taken on the line 6-6 in FIG. 3.

I claim:

The ornamental design for a barbecue grill, substantially as shown and described.
